UNITED STATES PATENT OFFICE

152,601

DESIGN FOR A COMBINATION SALT AND
PEPPER SHAKER

Marian S. Dillon, Youngstown, Ohio

Application August 15, 1946, Serial No. 132,553

Term of patent 3½ years

(Cl. D44—22)

To all whom it may concern:

Be it known that I, Marian S. Dillon, a citizen of the United States, residing at Youngstown, in the county of Mahoning and State of Ohio, have invented a new, original, and ornamental Design for a Combination Salt and Pepper Shaker, of which the following is a specification, reference being had to the accompanying drawing, forming a part thereof.

I claim:

The ornamental design for a combination salt and pepper shaker, as shown.

MARIAN S. DILLON.
